Application December 29, 1953, Serial No. 28,260

Term of patent 7 years

(Cl. D15—8)

To all whom it may concern:

Be it known that I, Gunnar G. Birkerts, a citizen of the Republic of Latvia, and a resident of Pontiac, in the county of Oakland and State of Michigan, have invented a new, original, and ornamental Design for a Stool or the like, of which the following is a specification, reference being had to the accompanying drawing, forming part thereof, in which:

Fig. 1 is a perspective view of a stool or the like, showing my new design;

Fig. 2 is an end elevational view thereof;

Fig. 3 is a side elevational view thereof; and

Fig. 4 is a top plan view of the structure shown in Figs. 1, 2 and 3.

The characteristic features of the design reside in the solid line portion.

I claim:

The ornamental design for a stool or the like, as shown and described.
